Filed Sept. 28, 1971, Ser. No. 184,657

Term of patent 14 years

Int. Cl. D6—06

U.S. Cl. D6—97

FIG. 1 is a view in perspective of a front cover for a bathroom tissue dispenser showing my new design; FIG. 2 is a front view in elevation of the same; FIG. 3 is a top view of the same; FIG. 4 is a bottom view of the same; FIG. 5 is a right side view in elevation of the same; and

FIG. 6 is a left side view in elevation of the same. The fragmentary broken line representation of a wall and the broken line representation of a tissue dispenser in FIG. 1 is for purposes of illustration only.

I claim:

The ornamental design for a front cover for a bathroom tissue dispenser, substantially as shown and described.
